UNITED STATES PATENT OFFICE.

FRANCIS JERDONE, JR., OF TOLEDO, OHIO, ASSIGNOR TO INDUSTRIAL RESEARCH CORPORATION, OF TOLEDO, OHIO, A CORPORATION OF DELAWARE.

FUEL-RESERVE-SUPPLY SYSTEM.

1,357,987.

Specification of Letters Patent. Patented Nov. 9, 1920.

Application filed April 8, 1919. Serial No. 288,495.

To all whom it may concern:

Be it known that I, FRANCIS JERDONE, Jr., residing at Toledo, Ohio, have invented certain new and useful Improvements in Fuel-Reserve-Supply Systems, of which I declare the following to be a full, clear, and exact description.

My invention relates to a fuel reserve supply system for internal combustion engines and has for its object to provide simple and inexpensive means by which a reserve supply of fuel may be carried in the main fuel supply tank from which fuel is fed to the engine.

Another object of the invention is to provide means for automatically closing the outlet passageway of a fuel supply tank when the fuel therein falls below a pre-determined point, the adjustment of said means to open said passageway being effected manually and the release of said means from adjusted position being dependent upon the rise of the liquid in the tank above said pre-determined point.

Another object of the invention is to provide, in combination with the vacuum fuel feed system of an internal combustion engine, an improved device for controlling a reserve supply of fuel in the main supply tank, which supply can be used only upon manual operation of the device after a pre-determined amount of fuel has been consumed, said device not requiring further manipulation until a new supply of fuel greater than the reserve supply has been placed in the tank and reduced to a pre-determined amount.

Another object of the invention is to provide an improved float actuated valve for controlling a reserve supply of fuel in a fuel supply tank connected with an internal combustion engine for supplying fuel thereto.

To these and other ends the invention comprises certain novel features of construction and arrangement of parts as will be herein-after more fully described and claimed, it being understood that various modifications in the detailed construction of the device may be made without departing from the spirit of the invention as expressed in the claims.

A structure illustrating one embodiment of my invention is shown in the accompanying drawing forming a part of this specification, in which:

Fig. I is a diagrammatic view embodying the invention.

Fig. II is a fragmentary, sectional elevation of a fuel tank with my invention applied thereto.

Fig. III is a top plan view of the arrangement shown in Fig. II.

Fig. IV is a sectional plan taken on the line IV—IV of Fig. II.

Fig. V is a fragmentary sectional elevation of a slightly modified form of the invention.

Fig. VI is a sectional plan taken on the line VI—VI of Fig. V and

Fig. VII is a detailed sectional plan taken on line VII—VII of Fig. V.

Like reference characters throughout the several views of the drawing indicate corresponding parts.

In the construction of a fuel reserve supply system, it is desirable to provide mechanism for controlling the discharge of fuel from the supply tank, which mechanism will not require manipulation after it has been adjusted to position to permit the discharge of the reserve supply of fuel carried in the tank, and in carrying out the present invention I have provided means for accomplishing this result.

Referring to the drawing, 10 represents an internal combustion engine such as is used on motor driven vehicles. A vacuum feed tank 11 is connected with the manifold 12 of the engine by means of a conduit 13, and the carbureter 14 of the engine is connected with said vacuum tank by means of a conduit 15, while the main fuel supply tank 16 is connected with said vacuum tank by means of a conduit 17, all as shown in Fig. I. Although in the present instance I have shown the tank connected with the manifold of an internal combustion engine, it will be understood that any other suitable form of aspirator may be employed for forcing the fuel from the tank to any desired point. In the top of the tank 16 I provide an opening 18 which is protected by a cover plate 18', constituting a part of the upper wall of the tank and secured thereon by any suitable means, as by soldering. Projecting into the tank through the cover plate 18' is a tube 19 threaded at its upper end to receive the nut 20 on the underside of said plate, and the member 21 on the upperside of said plate, the conduit 17 being connected 110

with the member 21 by means of a reducing coupling 22, as shown at the left of Fig. I. The lower end of the tube 19 which projects to a point adjacent the bottom of the tank 5 is provided with a cap 23, the upper edge of which is beveled outwardly as indicated at 24 to receive the inwardly beveled edge 25 of the sleeve 26, which is slidably mounted upon the tube, and which is provided with 10 a float 27 for raising the sleeve when the liquid in the tank is increased above a pre-determined amount. The sleeve 26 is preferably extended through the float as indicated in Fig. II, although it may be connected directly to the bottom of the float if 15 desired. The tube 19 is provided at a point just above the upper edge of the cap 23 with fuel inlet apertures 28 which are closed by the sleeve when the liquid in the tank is 20 reduced to a pre-determined amount. The float controlled sleeve 26 constitutes a valve for automatically closing the passageways 28 when the liquid in the tank is reduced to an amount sufficient to constitute the required 25 reserve supply of fuel, so that when the engine is stopped as a result of the closing of the valve, there will be sufficient fuel left to enable the car to be driven a considerable distance, whereby the driver is given an 30 opportunity to locate a filling station where he may secure a fresh supply of fuel. The float controlled valve on the tube 19 will open automatically only when a supply of fuel is placed in the tank greater than the 35 reserve supply, and when the valve is closed and it is not possible to immediately secure a new supply of liquid for the tank, the valve may be manually operated to open position to permit the use of the reserve supply of fuel. It is also desirable that when 40 the valve has been manually adjusted to open position that it be released automatically when a new supply of liquid is placed in the tank, thereby not requiring the attention of the driver until all but the reserve supply has been consumed. The means which I have provided for accomplishing this result comprises an adjustable rod 29 loosely projecting through an elongated 45 opening 30 in the cover plate 18' of the tank, the lower end of said rod being extended through a guide 31 secured to the side wall of the float 27 and through a plate 31' on the bottom of the float as shown in Fig. II, said 50 rod being provided at a point just beneath the plate 31' with a nut or head 32, which engages said plate to effect the raising of the float and valve when the rod is raised to the position shown by dotted lines in Fig. II. 55 Upon the cover plate 18' of the tank at a point adjacent the slot 30 therein is mounted an upstanding plate bracket 33 provided with communicating slots 34 and 34' for receiving the laterally projecting handle 35 of the rod 29 as shown in Figs. II and III.

The plate 33 is provided with two shoulders or points of support for the rod 29, as indicated at 36 and 36', at the base of the slots 34 and 34' respectively, the point 36 serving to support the rod in normal position as 70 shown by full lines in Fig. II, and the point 36' serving to support said rod in adjusted position as shown by dotted lines in said figure. The shoulder 36' is placed far enough above the shoulder 36 to insure the 75 clearance of the apertures 28 in the tube 19 by the sleeve 26 when the float is lifted to the position indicated by dotted lines in Fig. II. The shoulder 36' is placed to one side of the shoulder 36 so that when the 80 valve is in open position, the rod 29 will be inclined with respect to the tube 19. When a new supply of liquid is placed in the tank and the float thereby elevated, the guide plate 31 will slide a certain distance upon said rod and by reason of the inclination of the latter the plate will tend to wedge thereon and force the rod upwardly to cause the handle 35 to move out of the slot 34' over the inclined portion 37 of the bracket 90 33 until it passes the uppermost point 38, after which the handle will descend upon the outwardly inclined face 39 of the bracket to normal position within the slot 34 as shown by full lines in Fig. II. During this operation the plate 31' rides upon the rod to throw the upper end outwardly as the rod is raised such action being due to the pivoting of the rod upon the plate 31, said plate 31' serving to pull the lower end of the rod inwardly as 100 the float is raised. As a means for insuring the positive return of the rod to normal position when the handle is elevated above the point 38 I have provided a spring 40 coiled about the rod which has its upper end seated 105 on the plate 18', and its lower end anchored upon an enlargement 41 on the rod as shown in Fig. II. The spring 40 is tensioned a sufficient amount to insure the quick return of the rod and to prevent its rattling when the 110 car is in motion. Furthermore, when the rod is raised from normal position as indicated by dotted lines, the spring 40 will be slightly compressed thus serving to yieldingly hold the rod in adjusted position. 115 A slightly modified form of rod and rod holding means is provided in Figs. V to VII inclusive. In this modification the rod 42 is provided with an enlarged head or handle 43 normally resting upon the plate 44 secured 120 at one side of the cover plate 18' on the tank 16. The rod 42 immediately under the head 43 is provided with a reduced portion 45 which, however, is of a greater diameter than the rod, said portion 45 being movable 125 in an elongated opening 46 in the cover plate 18, and also in the larger portion of the key-hole slot 47 in the plate 44 which registers with the slot 46. When the rod 42 is in normal position the head 43 rests upon the plate 130

44 with the reduced portion 45 projecting through the keyhole slot 47 and opening 46 in the plate 18. When the rod is raised and inclined with respect to the tube 19, as 5 shown by dotted lines in Fig. V, the reduced portion 45 is seated upon the plate 44 with the rod extending through the narrow portion 48 of the keyhole slot, said rod being held in raised position within said slots by 10 means of a spring 49, one end of which is anchored at 50 to the rod, and the other at 51 upon a downwardly projecting member 52 secured to the plate 18, as shown in Fig. V. When the rod 42 is in normal position, the 15 enlarged portion 45 is yieldingly held by the spring 49 against the plate 44 at the point where the keyhole slot is reduced, and when said rod is raised from normal position to that indicated by dotted lines, the spring 49 20 is further tensioned and serves to yieldingly hold the rod in the reduced portion 48 of the keyhole slot until the rod is moved to release position by the upward movement of the float in the tank, it being understood that 25 as the float is elevated, the plate 31 will wedge upon the inclined rod and move it to the left until the enlarged portion 45 registers with the enlarged opening of the keyhole slot, at which time the spring 49 30 serves to depress the rod and move it back to normal position. The spring 49 is relatively light so that the buoyancy of the float is sufficient to overcome the resistance of the spring in tending to hold the rod in the position shown by dotted lines when the supply of liquid in the tank is increased above a 35 pre-determined amount.

It will be understood, of course, that the engine will not stop immediately upon the 40 closing of the valve in the main supply tank, as there will be sufficient fuel in the gravity feed tank and carburetor to supply the engine for a relatively short period of time, after which the driver's attention is 45 called to the fact that the fuel control valve is closed and must be set in open position. When the engine stops for lack of fuel in the carburetor, it must be started by external mechanism and kept going until sufficient 50 fuel is pumped into the gravity feed tank and fed to the carburetor to permit the engine to be run by the explosion of gas in the cylinders. A comparatively few revolutions of the crank shaft will suffice for this purpose, and this work may be performed by 55 the engine starter, or the engine may be cranked by hand if not provided with a self starter.

Having thus described my invention, what 60 I claim as new and desire to secure by Letters Patent is:

1. A liquid holding receptacle having an outlet passageway, a float controlled valve for said passageway, and a rod operatively 65 connected with the valve adapted when in

normal position to permit the closing of the valve and arranged to be shifted laterally upon the tank to support said valve in open position and to be released by upward movement of the float in the receptacle to 70 permit the return of the rod to normal position.

2. A liquid holding receptacle having an outlet passageway, an aspirator connected therewith, a float controlled valve for said passageway, a rod operatively connected with the valve and adapted when in normal position to permit the closing of the valve and arranged to be shifted laterally to support said valve in open position and to be released by upward movement of the float in the receptacle and a spring adapted to return the rod to normal position when released. 75

3. A liquid holding receptacle having an outlet passageway, a float controlled valve for said passageway, a rod operatively connected with the valve and adapted when in normal position to permit the closing of the valve and arranged to be shifted laterally to support said valve in open position and to be released by upward movement of the float in the receptacle, and means for insuring the return of said rod to normal position when released. 80

4. A liquid holding receptacle having an outlet passageway, a float controlled valve for said passageway, a member for lifting said valve, said member being adapted to be deflected out of normal position to hold said valve open, and means for holding said member in adjusted position, said member being automatically released from said holding means when a predetermined amount of liquid is placed in the receptacle. 100

5. A liquid holding receptacle having an outlet passageway, an aspirator connected therewith, a float controlled valve for said passageway, a member for lifting said valve, said member being adjustable laterally of its normal position to hold said valve open, and means for holding said member in adjusted position, said lifting member being automatically released from said holding means when a pre-determined amount of liquid is placed in the receptacle. 105

6. A liquid holding receptacle having an outlet passageway, an aspirator connected with said passageway, a float controlled valve for said passageway, a lifting member for said float and valve, said member being adjustable laterally of its normal position to hold said valve open, means for holding said member in adjusted position, said member being automatically released from said holding means when a pre-determined amount of liquid is placed in the receptacle, and means for returning said member to normal position when released. 120

7. A liquid holding receptacle having an 125

outlet passageway, a float controlled valve for said passageway, a plate upon said receptacle, a rod connected with said float controlled valve and adapted to be supported upon said plate in two positions of adjustment requiring the rod to be shifted laterally and longitudinally, movement of the rod from one of said positions being effected manually and from the other automatically when a pre-determined amount of liquid is placed in the receptacle.

8. A liquid holding receptacle having an outlet passageway, an aspirator connected therewith, a float controlled valve for said passageway, a plate member upon said receptacle, an operating member connected with said float controlled valve and adapted to be deflected laterally upon the receptacle and to coöperate therewith to hold the valve open, movement of said operating member in one direction being effected manually and in the opposite direction by the action of the float when the tank is refilled.

9. A liquid holding receptacle having an outlet passageway, a float controlled valve for said passageway, a holder upon said receptacle having a slot therein and a member connected with said float controlled valve and movable laterally in said slot to two positions of adjustment, movement of said member from one of said positions being effected manually and from the other automatically when a pre-determined amount of liquid is placed in the receptacle.

35 10. A liquid holding receptacle having an outlet passageway, a float controlled valve for said passageway, a holder upon said receptacle having a slot therein and a member connected with said float controlled valve and movable laterally in said slot to two positions of adjustment, movement of said member from one of said positions being effected manually and from the other automatically when a pre-determined amount of liquid is placed in the receptacle and yieldable means for holding said member in its separate positions of adjustment.

11. A liquid holding receptacle having a tube projecting therein provided with an inlet passageway, a float slidably mounted upon said tube, a valve connected with said float for controlling said passageway, a plate member upon said receptacle and a lifting member connected with said float and adapted to be adjusted laterally upon said plate member to two positions, adjustment of said member in one direction being

effectuated manually and in the other automatically when a pre-determined amount of liquid is placed in the receptacle. 60

12. A liquid holding receptacle having a tube projecting therein, provided at its lower end with an opening, an aspirator connected with said tube, a float slidably mounted on said tube, a sleeve connected with said float and slidably mounted upon said tube for controlling said opening, a plate member upon said receptacle, a rod connected with said float and adapted to be supported upon said plate member in two positions of adjustment requiring both lateral and longitudinal movement of the rod, adjustment of the rod to one of said positions being effected manually and to the other automatically when a pre-determined amount of liquid is placed in the receptacle, and means serving to hold said rod in yielding engagement with said plate member in either of its positions of adjustment. 70

13. In a fuel reserve supply system, the combination with the manifold and carburetor of an internal combustion engine and the fuel supply tank therefor, of a float controlled valve for the supply pipe leading from said tank, a holder upon said tank, a lifting member connected with said float controlled valve and adapted to be supported upon said holder in two positions of adjustment, requiring lateral movement of the lifting member, adjustment of said lifting member in one direction being effected manually and in the other automatically when a pre-determined amount of liquid is placed in the receptacle. 80

14. In a fuel reserve supply system, the combination with the manifold and carburetor of an internal combustion engine and the fuel supply tank therefor, of a float controlled valve for the supply pipe leading from said tank, a holder upon said tank, a lifting member connected with said float controlled valve and adapted to be supported upon said holder in two positions of adjustment, requiring lateral movement of the lifting member, adjustment of said lifting member in one direction being effected manually and in the other automatically when a pre-determined amount of liquid is placed in the receptacle and means for yielding holding said lifting member in each 100 of its positions of adjustment. 90

In testimony whereof I affix my signature.

FRANCIS JERDONE, JR.
